Primary Examiner — David Muller

(57) **CLAIM**

I claim the ornamental design for a: grill/register takeoff, as shown and described.

DESCRIPTION

FIG. 1 is a perspective view of grille/register takeoff.
FIG. 2 is a top view thereof.

FIG. 3 is a side elevation view thereof.

FIG. 4 is an end elevation view thereof; and,

FIG. 5 is a plan view showing the grille/register takeoff in an unfolded flat pattern configuration.

1 Claim, 4 Drawing Sheets

FIG. 1

FIG. 2

FIG. 3

FIG. 4

FIG. 5
